UNITED STATES PATENT OFFICE

105,687

DESIGN FOR A TRAY OR SIMILAR ARTICLE

Emile Bode, Paris, France, assignor to Societe Anonyme des Etablissements Elesca & Maille Reunis (L. K. S. M.), Paris, France, a corporation of France

Application April 22, 1937, Serial No. 68,921

Term of patent 3½ years

To all whom it may concern:

Be it known that I, Emile Bode, a citizen of the Republic of France, residing at Paris, France, have invented a new, original, and ornamental Design for a Tray or Similar Article of which the following is a specification, reference being had to the accompanying drawing, forming a part thereof.

In the drawing:

Fig. 1 is a perspective view of the tray or similar article, showing my design;

Fig. 2 is a side view; and

Fig. 3 is a bottom plan view thereof.

I claim:

The ornamental design for a tray or similar article as shown.

EMILE BODE.
